J. C. MABRY

GARMENT SUPPORTING DEVICE

Filed July 14, 1924

INVENTOR.

John C. Mabry
BY
Warren D. House
His ATTORNEY.

witness:

R. C. Hamilton

UNITED STATES PATENT OFFICE.

JOHN C. MABRY, OF KANSAS CITY, MISSOURI.

GARMENT-SUPPORTING DEVICE.

Application filed July 14, 1924. Serial No. 725,890.

To all whom it may concern:

Be it known that I, JOHN C. MABRY, a citizen of the United States, residing at Kansas City, in the county of Jackson and State of Missouri, have invented a certain new and useful Improvement in Garment-Supporting Devices, of which the following is a specification.

My invention relates to improvements in garment supporting devices. While it is adapted for various uses, it is particularly well adapted for use in connection with trouser supporting suspenders worn inside of a shirt.

One of the objects of my invention is to provide novel garment supporting means which is simple, cheap, durable, not liable to get out of order, which prevents undue wear of a shirt engaged thereby, which will not cause excessive puckering or wrinkling of the shirt, which permits the easy and quick attachment to or detachment from the garment of the suspenders, and which is not liable to accidental detachment upon bending of the body.

A further object of my invention is the provision of novel button securing means by which the ends of the button are held closely attached to the garment to avoid endwise tilting with respect thereto, and with which the shirt is held from being pulled by the loop under the lower end of the button, and which serves as a cushion against which the shirt bears at the lower end of the button.

Still another object of my invention is to provide a novel button that lies flatwise against the garment and is not liable to have its edges press against and hurt the body of the wearer.

My invention provides still further a button and loop engaging therewith, between which is engaged a relatively large amount of the goods of the shirt, thereby distributing the strain over a relatively large area.

My invention further provides a novel loop adapted for efficient use in connection with my improved button.

The novel features of my invention are hereinafter fully described and claimed.

In the accompanying drawing, which illustrates the preferred embodiment of my invention,

Fig. 1 is an inside elevation showing my improved garment supporting device in operative position, portions of the suspenders, shirt and trousers being shown.

Fig. 2 is a perspective view of the parts shown in Fig. 1, the loop being shown detached from the button.

Fig. 3 is a vertical sectional view on the line 3—3 of Fig. 1.

Fig. 4 is an elevation, partly broken away, of the loop.

Fig. 5 is a horizontal section on the line 5—5 of Fig. 1.

Fig. 6 is a perspective view of my improved button.

Similar reference characters designate similar parts in the different views.

1 designates my improved button, which is preferably provided with flat parallel sides and which is provided with two vertical parallel side edges 2, and which has, preferably, a rounded lower end edge 3, which merges with the edges 2. For receiving securing means, such as threads 4, the button is provided adjacent to its upper and lower ends respectively with two transverse holes 5.

The securing threads 4 engage the garment, such as trousers 6, in the usual manner and extend through the holes 5, and across the upper and lower ends of the button 1. The threads 4 at the lower end of the button preferably project, as shown, below the edge 3 and serve as a cushion for the shirt 7 and prevent the latter from being pulled under the lower edge of the button by the loop when the parts are disposed in operative position, as shown in Figs. 1 and 3.

For engaging the button to support the trousers 6 from a suspender strap 8, a portion of which is shown, I provide a loop, which is preferably formed from a piece of wire 9, the end portions of which are straight and disposed in horizontal end to end alignment and which extend into a ferrule 10, which is attached in the usual manner to the suspender strap 8.

The wire 9 at the lower end of the loop is U-shaped, the arms of which for substantially the length of the button 1 being parallel, and above the button diverging to the outer ends respectively of the end portions of the wire.

The loop 9 thus formed provides an opening 11, through which the button 1 is adapted to be passed between the diverging portions of the loop. The opening 11 below the diverging portions of the loop is narrower than the width of the button 1 and has parallel vertical sides.

In attaching the suspender to the button, when the suspenders are worn inside the shirt, the button 1 covered by the shirt 7 is passed through the loop 9 between the diverging portions thereof, following which the loop is pulled upwardly to the position shown in Figs. 1 and 3, whereby the loop and button are firmly fastened together.

To detach the loop from the button, the 10 operation just described is reversed.

By having the button provided with the parallel side edges, and the loop having the parallel portions disposed between the button and the trousers, a relatively large area 15 of the shirt 7 is engaged, thereby greatly reducing the pulling strain on the shirt, such as ordinarily occurs in devices of this character in which round buttons are used. Furthermore, there is a minimum of puckering 20 and wrinkling of the shirt at the side edges of the button.

In devices of this character, the greatest wear on the shirt is at that portion that is engaged by the loop below the button, due to 25 the goods of the shirt being pulled by the loop under the lower end of the button. In my improved construction, the lower threads 30 serve as a cushion, against which the shirt bears, and also prevent the shirt being pulled by the loop under the lower end of the button. This eliminates a great deal of wear, where the most wear usually occurs.

As the button 1 is firmly attached to the trousers at its upper and lower ends, and due 35 to the oblong shape of the button, the suspender loop 9 at the front or sides of the trousers cannot be accidentally detached in the bending of the body, such as occurs with the usual circular button and ordinary loop. 40 By means of this construction, it is not necessary to have a restricted portion, such as is commonly provided in the usual loop to prevent the button slipping upwardly and out of detachment with the loop. By having 45 the sides of the lower portion of the opening 11 parallel, much wear of the goods of the shirt is eliminated.

As the button is attached at its upper and lower ends to the trousers and is flat at the 50 side next to the trousers, it cannot tilt at its upper or lower ends from the trousers, but is firmly held thereto, thus enabling the wearer to easily manipulate the button and loop in making a connection or disconnection.

As both sides of the button are flat and 55 parallel, the button does not stand away from the trousers at its edges, as does the usual button having the central securing threads. This provides a structure in which 60 the edges of the button will not bear against and hurt the body of the wearer.

I prefer to make the button 1 of some flexible material, preferably leather. A button of such material will produce a minimum 65 of wear upon the shirt. Leather has

flexibility and it also has sufficient rigidity to effect a firm fastening for fabric engaged therewith with a minimum of slippage and wear. It is easily manipulated in the process of its manufacture into a button, and has great durability, and is not liable to cut or wear securing threads.

I do not limit my invention to the structure shown and described, as many modifications within the scope of the appended 75 claims may be made without departing from the spirit of my invention.

What I claim is:

1. A button of the kind described comprising an oblong flat flexible body having a 80 rounded end edge and parallel side edges merging into said end edge and having through the body from side to side two holes respectively adjacent to the ends of the body adapted to receive fastening means.

2. In a garment supporting device, a garment, a flat flexible button mounted thereon having a hole therethrough, and securing threads engaging the garment and extending across the lower end of the button and through the hole thereof and adapted to be engaged by a fabric to be attached to the garment.

3. In a garment supporting device, a garment, a flat flexible button mounted thereon having vertical parallel side edges and a rounded lower end, and securing threads engaging the garment and the button and extending across and projecting below the lower end of the button and adapted to be engaged by a fabric to be attached to the garment.

4. In a garment supporting device, a garment, a button mounted thereon having vertical parallel side edges and two holes therethrough, and securing threads engaging the garment and the button and extending through said holes and across the upper and lower ends of the button, said threads which extend across the lower end being adapted to be engaged by a fabric to be attached to the garment.

5. In a garment supporting device, a garment, a flexible button mounted thereon having flat front and rear sides and vertical parallel side edges, and a rounded lower end edge merging into said side edges, securing threads engaging the garment and the button and extending across and projecting below the lower edge of the button, and adapted to be engaged by a fabric to be attached to the garment, and a loop having an opening adapted to receive therethrough said button, the lower end portion of the opening being narrower than the width of the button and having vertical parallel sides.

In testimony whereof I have signed my name to this specification.

JOHN C. MABRY.
